UNITED STATES PATENT OFFICE

2,436,810

KNIFE SHARPENER

George M. Jones, Jenkintown Manor, Pa., assignor to Luxor Corporation, Philadelphia, Pa., a corporation of Pennsylvania

Application November 1, 1945, Serial No. 626,008

2 Claims. (Cl. 76—87)

1

This invention relates to sharpeners for knives and like edged tools. This sharpener is of the type employing hardened metal discs.

Among the objects of this invention is to provide a knife-sharpener of the type employing hardened metal discs which has a minimum number of parts and maximum simplicity and which shall be convenient to manufacture by mass production methods such as those including metal stamping and sheet metal bending steps or operations.

This invention has as further objects the provision of a knife-sharpener of this type which can be made available at a low cost to the consumer because it can be manufactured economically, and which is convenient and efficient in use.

For the purpose of illustrating the invention, there are shown in the accompanying drawings forms thereof which are at present preferred, although it is to be understood that the various instrumentalities of which the invention consists can be variously arranged and organized and that the invention is not limited to the precise arrangements and organizations of the instrumentalities as herein shown and described.

In the drawings, in which like reference characters refer to like elements,

Figure 1 represents a perspective view of the improved knife-sharpener in use

Figure 2 represents a view in vertical cross section along the line 2—2 of Figure 1 on an enlarged scale

Figure 3 represents a view in substantially horizontal cross section along line 3—3 of Figure 2 on an enlarged scale

Figure 4 represents a perspective view on substantially same scale as Figure 1 showing the knife sharpener during its process of manufacture.

That embodiment of my novel knife-sharpener, selected from among others for illustration in the drawing and description in the specification, comprises a support generally indicated at 10. The support 10 may conveniently be made of a single sheet or blank of metal. The support 10 is provided with a base or stand 11 having perforations 12 passing therethrough for the reception of screws 112 or other fastening means which serve to secure the knife-sharpener in position on a table-top or like convenient location. At one edge, base 11 has a fold or bend indicated at 13 from which rises a body 14. In fold 13 are one or more indentations 15 which form stiffening ribs 16 in the opposite or inner face of the fold 13. At its upper portion, body 14 is divided by

2

a notch 17 so that the upper part of the body is formed into two parts 18 conveniently termed "heads." Each head 18 has a boss or projection 19 formed thereon as by being stamped or pressed therefrom. The interengaging part of heads 18 and of bosses 19 may have one or more stiffening ribs 20 thereon. As is best seen in Figure 4, each head 18 has an ear 21 projecting from the side thereof. Discs 22 of metal, such as hardened steel having precision-ground edges or rims, are mounted on bosses 19 by means of perforations 23 passing through the discs 22. The discs 22 are secured in position on the bosses 19 by means of the ears 21 which are conveniently bent over against the faces of the discs 22 after the discs 22 have been placed upon the bosses 19. This operation is disclosed while it is in process in Figure 4. Each disc 22 fits snugly on a boss 19 and is not vertically tiltable or cantable about the axis of the boss. Each of the ears 21 is bent around the rim or edge of one of the discs 22 and abuts against a part of the rim or edge of the disc on the opposite side of the pivot or center of the disc to that part 24 of the edge or rim of the disc which forms the sharpening location or point of contact with the knife blade being sharpened. Therefore any stress or pressure which the knife or blade being sharpened puts upon the discs is taken or resisted by the ears 21 as well as by the bosses 19. The discs 22 are located with their rims or edges substantially in contact as is indicated at 24 and are aligned so that the major dimension of each of the discs 22 is located in the same plane or surface. In other words, the discs 22 are in edge-to-edge contact and do not overlap.

The method of manufacturing this improved knife-sharpener is as follows. The support 10 as a whole, is cut out of sheet stock as by blanking or stamping. The bosses 19 and the reinforcing ribs 20 therefor may be formed by this same operation. The base 11 can then be made by bending the blank about the fold 13, the stiffening ribs 16 being formed simultaneously. The support 10 may then be placed with the body 14 horizontal and the bosses 19 uppermost, the discs 22 placed upon the bosses 19, and the ears 21 bent over against the upper faces of the discs 22. Since the discs 22 make a straight-line contact as at 24 and are stressed toward each other and also fit snugly upon the bosses 19, they tend to resist displacement during the sharpening operation so that there is no excessive unfolding stress upon the ears 21 such as would otherwise re-

quire the provision of a backing or reenforcement for said ears.

Figure 1 shows the mode of operation of this knife-sharpener in use. A knife is placed between the discs 22 so as to overlie the notch 17. The knife is then drawn along its length with its blade or edge between the edges of the discs. These hardened steel discs impart a sharp edge or cutting surface to the knife.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described my invention what I claim as new and desire to protect by Letters Patent is:

1. A knife-sharpener including a one-piece support of sheet-metal comprising a flat elongated base, a disc-supporting portion formed at an acute angle with said base and separated therefrom by a fold-line extending substantially more than half the length of said base, said portion being centrally-notched to provide a pair of side-by-side co-planar disc-supporting members, a disc-supporting boss formed integrally on each of said members, and a disc-retaining ear formed integrally on the outer edge of each of said members; and including a pair of centrally-apertured sharpening discs rotatably mounted on said bosses in co-planar relationship, said discs having cylindrical sharpening edges disposed in abutting relationship at the notch of said disc-supporting portion, said ears being folded around said discs generally in diametrically-opposed relationship to the point of abutment and serving to retain said discs upon said bosses in vertically immovable and uncantable position.

2. A knife-sharpener including a one-piece support of sheet-metal comprising a flat elongated base, a disc-supporting portion formed at an acute angle with said base and separated therefrom by a fold-line extending substantially more than half the length of said base, a plurality of stiffening ribs pressed outwardly from and extending transversely across the inner side of said fold-line, said portion being centrally-notched to provide a pair of side-by-side co-planar disc-supporting members, a disc-supporting boss formed integrally on each of said members, and a disc-retaining ear formed integrally on the outer edge of each of said members; and including a pair of centrally-apertured sharpening discs rotatably mounted on said bosses in co-planar relationship, said discs having cylindrical sharpening edges disposed in abutting relationship at the notch of said disc-supporting portion, said ears being folded around said discs generally in diametrically-opposed relationship to the point of abutment and serving to retain said discs upon said bosses in vertically immovable and uncantable position.

GEORGE M. JONES.
